(57) CLAIM

The ornamental design for a tote bag, as shown and described.

DESCRIPTION

FIG. 1 is a perspective view of one embodiment of the tote bag in accordance with the present invention with closed legs.

FIG. 2 is a front view of the embodiment of FIG. 1.

FIG. 3 is a back view of the embodiment of FIG. 1.

FIG. 4 is a right view of the embodiment of FIG. 1.

FIG. 5 is a left view of the embodiment of FIG. 1.

FIG. 6 is a top view of the embodiment of FIG. 1.

FIG. 7 is a bottom view of the embodiment of FIG. 1.

FIG. 8 is a perspective view of another embodiment of the tote bag in accordance with the present invention with open legs.

FIG. 9 is a front view of the embodiment of FIG. 8.

FIG. 10 is a back view of the embodiment of FIG. 8.

FIG. 11 is a right view of the embodiment of FIG. 8.

FIG. 12 is a left view of the embodiment of FIG. 8.

FIG. 13 is a top view of the embodiment of FIG. 8; and, FIG. 14 is a bottom view of the embodiment of FIG. 8.

The broken lines, including those indicating straps and stitching on the surface of the article, are for illustrative purposes only and form no part of the claimed design.
